UNITED STATES PATENT OFFICE.

WILLIAM R. HOWARD, OF WASHINGTON, DISTRICT OF COLUMBIA.

DRILLING TOOL.

Application filed August 3, 1918, Serial No. 248,114. Renewed January 19, 1923.

To all whom it may concern:

Be it known that I, WILLIAM R. HOWARD, a citizen of the United States, and a resident of the city of Washington, District of Columbia, have invented certain new and useful Improvements in Drilling Tools, of which the following is a specification.

This invention relates to improvements in drilling tools and refers more particularly to a device for cutting through rock or similar formations in the drilling of oil wells.

In the drilling of oil wells, particularly in deep wells the standard rotary drilling rigs cut through the relatively soft earth without much difficulty. When, however, rock formations are encountered, it is necessary to put on a rock or roller bit in order to cut through the rock. This operation is exceedingly slow and it frequently takes longer to cut through a relatively few feet of rock than it does to drill the entire rest of the well through soft earth. Difficulty is also experienced in twisting off the drill stem which generally consists of a series of connected pipe sections.

The object of the present invention is to provide a construction which will readily and quickly drill through rock without the danger of injuring or breaking the drilling mechanism and which also can be applied to standard rotary drilling rigs.

To the above end, I provide the motive power for the drilling tool at a point in which the tool operates. This is accomplished by connecting a motor to the lower end of the drill stem and then operatively connecting the armature shaft of the motor to the cutting bit or tube. This motor is controlled by electrical conductors extending up through the drill stem to the operator. Means are also provided for reaming out the rock core at the proper time. The arrangement is such as to avoid any necessity of rotating the drill stem while the rock cutting operation is going on. It will be noticed, however, that, if additional speed is required, the drill stem may be rotated simultaneously with the cutting tool or, on the other hand, the cutting tool may be ro-

tated by the turning of the drill stem. After the rock is cut through, the drill stem is removed from the hole and the motor and rock bit detached from the drill stem and the operation continued with the proper bit for drilling the remainder of the hole.

In the drawings:

Fig. 1 is a vertical view partly in elevation and partly in section with parts broken away to reduce the size of the drawing showing my improved apparatus.

Fig. 2 is an enlarged detail view of the upper end of the apparatus.

Fig. 3 is a similar view showing the manner of connecting the motor to the drill stem.

Fig. 4 is a detail view of the cutting member connected to the armature shaft of the motor.

Fig. 5 is a bottom plan view on the line 5—5 of Fig. 4.

Fig. 6 is a sectional view taken on the line 6—6 of Fig. 3.

Referring to the drawings, 1 designates a platform, upon which is mounted a standard rotary driving member having the usual turn table 2, gripping wheels 3 and drive belt 4 with the usual connecting gears. The arrangement is such that the drill stem 5 can be rotated and also raised and lowered. This drill stem 5 is made up of pipe sections suitably screwed together and is adapted to extend down into the hole to be drilled. As the hole is drilled, it is, of course, provided with the usual casing 6.

When rock is encountered, it is necessary to remove the usual drilling tool and put on a rock bit. As before stated, however, drilling through rock is a slow and very unsatisfactory operation with the present devices now in use. To overcome the difficulties attendant on such constructions, I connect to the lower end of the drill stem a motor 7 enclosed in a jacket 8 of the proper shape and size to fit easily within the casing.

The bottom of the drill stem 5 may be attached to the top of the jacket 8 by any suitable flange joint or screw joint as it would be attached to the regular fish-tail or rock bit. The motor 7 is provided with a

square shaft 9 connected with and extending from the top of said motor up through a square hole at the top of the jacket 8 (Figs. 3 and 6), and of sufficient length to permit 5 the motor and cutting member 10 to be raised or lowered inside the jacket 8 for a distance equal to at least the depth of the core socket of the cutting member 10. The motor 7 with the cutting member 10 may 10 be raised or lowered by means of a cable 11, extending up through the drill stem to suitable apparatus for lifting, which cable conveys the conductors 12 necessary to operate the motor. To the armature shaft 13 15 of the motor, is secured a rock cutting tool 10. This tool 10 is provided at its lower edge with cutting bits 14, the arrangement being such that as it is rotated, it will cut through rock. When a core of sufficient 20 length has been cut out, the reaming tools 15 will be put into operation. Two or more of these can be placed in the walls of the cutting member 10 as shown in Fig. 4 and Fig. 5. In order to project the reaming 25 tools 15 into the core which is to be cut off and lifted out of the hole, a rod 16 is provided so that when the cutting member has made its trip downward the length of the core socket, the projection 17 at the bottom 30 of the jacket 8, comes in contact with a rocker arm 18 and it is so arranged as to push down the rod 16 against the pressure of a spring 19. When the cable 11 is raised, the contact of the projection 17 and rocker 35 arm 18 is broken and the spring 19 returns the rod 16 to its original position. When the rod 16 is pushed downward as above described, the co-operating beveled faces, one 40 on the lower end of the rod 16 and one on the end of the reaming tool 15, come together in such a manner as to push out the reaming tool 15 into the core which is to be cut off. The reaming tools 15 are normally held outwardly by the springs 20. 45 It will be noted that the projection 17 and rocker arm 18 may be brought into contact either by the rocker arm 18 traveling downward, until contact is made, or jacket 8 may be raised by means of the drill stem 50 being lifted until projection 17 comes in contact with rocker arm 18, on its way upward, thereby making it possible to cut off any length of core desired.

Holes 21 (Fig. 3) are provided at the bottom 55 of the drill stem in order to allow water which is being pumped down through the drill stem to get out into the hole and return upward and over the casing head when such is necessary, and which will permit the drilling operations to be carried on as herein described, at any distance below the bottom of the set casing without danger of "sticking" the drill stem.

To prevent water from getting into the motor the outlets of the jacket 8 which surrounds the motor are packed off at 22, 23, and 24. 65

I claim as my invention:

1. In a drilling apparatus, the combination with a drill stem, of a hollow jacket member secured to the lower end of the drill stem, a motor enclosed in said jacket, means for controlling the operation of said motor, from the ground, a cutting tool projecting into said jacket, operative connections between the motor and cutting tool for rotating the latter, and cutting bits carried by the tool. 70

2. In a drilling apparatus, the combination with a drill stem, of a hollow jacket member secured to the lower end of the drill stem, a motor enclosed in said jacket, means for controlling the operation of said motor, from the ground, a cutting tool projecting into said jacket, operative connections between the motor and cutting tool for rotating the latter, cutting bits carried by the tool, reaming tools carried by the tool, and means for moving said reaming tools into and out of operative position. 80

3. In a drilling apparatus, the combination with a drill stem, of a hollow jacket member secured to the lower end of the drill stem, a motor enclosed in said jacket, means for controlling the operation of said motor, from the ground, a cutting tool projecting into said jacket, operative connections between the motor and cutting tool for rotating the latter, cutting bits carried by the tool, reaming tools carried by the tool, means for moving said reaming tools into and out of operative position, said moving means comprising spring leverage mechanism adapted to have operative engagement with the jacket. 90

4. In a drilling apparatus, the combination with a drill stem, of a hollow jacket member secured to the lower end of the drill stem, a motor enclosed in said jacket, means for controlling the operation of said motor, from the ground, a cutting tool projecting into said jacket, operative connections between the motor and cutting tool for rotating the latter, cutting bits carried by the tool, a rotary drilling rig, operative connections between said rig and the drill stem whereby the cutting tool may be actuated either through the motor or the action of the drill stem or jacket or both. 100

5. In a drilling apparatus, the combination with a drill stem, of a hollow jacket member fixedly secured to the lower end thereof, a hollow cylindrical cutting tool projecting into said jacket, cutting bits extending outwardly from the periphery of said tool, reaming tools adapted to project inwardly from the periphery of said tool, and means for 110

moving said reaming tools into and out of operative position and means for rotating the tool.

6. In a drilling apparatus, the combination with a drill stem, of a hollow jacket member fixedly secured to the lower end thereof, a hollow cylindrical cutting tool projecting into said jacket, cutting bits extending out-

wardly from the periphery of said tool, reaming tools adapted to project inwardly from the periphery of said tool, and means for moving said reaming tools into and out of operative position, said means comprising spring leverage mechanism controlled by said jacket member. 10

WILLIAM R. HOWARD.
